CHRISTMAS TREE ORNAMENT

Otto Kadmon and Alice Kadmon, both of 144-37 76th
Road, Flushing, N.Y. 11367
Filed Mar. 1, 1967, Ser. No. 6,007

Term of patent 7 years

(Cl. D29—1)

FIG. 2 is a side elevational view thereof, and
FIG. 3 is a rear elevational view thereof.

We claim:

The ornamental design for a Christmas tree ornament, substantially as shown.
